JOHN P. FERRIS, OF MILWAUKEE, WISCONSIN, ASSIGNOR TO THE OILGEAR COMPANY,
OF MILWAUKEE, WISCONSIN, A CORPORATION OF WISCONSIN

PUMP

Application filed June 20, 1927. Serial No. 199,925.

This invention relates to variable delivery pumps for use primarily in effecting the hydraulic operation of machine tools and the like.

5 One object of the present invention is the provision of a self contained pump unit embodying driving and control mechanism so constructed and arranged as to permit a ready application, and removal, of the unit within 10 and from the frame of the machine to be driven. The machine frame may thus be utilized as a pump housing, to thereby effect an economy in space as well as cost. At the same time ready access to the pump parts, for 15 inspection and repair, is afforded by virtue of the ease with which the unit may be removed from within the frame.

Another object is the provision of a liquid seal for a gear pump or the like which will 20 prevent the admission of air thereto when placed outside of the supply reservoir.

Another object is the provision of improved means for regulating and controlling the rate and direction of flow in a pump fed 25 hydraulic circuit. This is accomplished by combining a distributing valve for controlling the direction of flow with an independently operable displacement regulating means for controlling the rate of flow.

30 Another object is the provision of means for regulating pump displacement which will permit manual adjustment to determine the initial rate of pump delivery and operable to effect a predetermined increase in pump 35 delivery and a return to the rate initially set.

Other objects and advantages will appear from the following description of an illustrative embodiment of the present invention.

40 In the drawings:

Figure 1 is a front elevation of a pump mechanism constructed in accordance with the present invention.

Fig. 2 is a vertical sectional view, taken 45 substantially along the line 2—2 of Figure 1, and illustrating its application to the frame of a machine to be driven.

Fig. 3 is a vertical sectional view, taken along the line 3—3 of Figure 2.

50 Fig. 4 is a vertical sectional view, taken

in the same plane but looking in the opposite direction.

Fig. 5 is a fragmentary rear elevation.

Fig. 6 is a horizontal sectional view.

Figs. 7, 8, 9 and 10 are sectional views of 55 the valve shown in Figure 3, showing the same in various characteristic positions.

The pump selected for illustration includes a heavy plate 10, constituting a support for the various operating and control parts of the 60 pump, and adapted for direct application to the main frame 11 of the machine to be driven.

In Figure 2 the plate 10 is shown removably secured over an opening 12 in the frame 11 with the operating parts of the pump 65 housed within the frame. The operating parts are carried by a main casting 13 removably secured to and against the inner face of the plate 10 by appropriate means such as bolts 14. A drive shaft 15, extending through 70 alined openings 16 and 17 in the plate 10 and casting 13, is journaled in appropriate anti-friction bearings 18 and 19 and carries a pulley 20 or other suitable driving means upon the exposed end thereof. Bearing 18 is retained in a chamber 21 formed in the plate 10 and closed by a removable cover plate 22, which cooperates with suitable packing 23 and packing nut 24 to seal the chamber 21 75 against leakage. The other bearing 19 is seated within an open chamber 25 formed in the rear face of the casting 13.

Two intermeshing gears 26 and 27 are snugly housed within a chamber 28 formed in the front face of the casting 13 and closed by the 80 rear face of the plate 10. These gears cooperate with each other and with the chamber to provide a gear pump of a well known type. Gear 26 is keyed to and driven by the shaft 15 while gear 27 rotates upon a stud 29 rigidly anchored in the casting 13. The gear pump draws liquid from an appropriate sump 30, provided within the machine frame 11, through a pipe 31, which communicates with the chamber 28 through a passage 32 in the 85 casting 13 at one side of the gears, and discharges this liquid through a port 33 formed in the rear face of the plate 10 and disposed at the other side of the gears. Port 33 communicates with an inclined passage 34 formed 90

in the plate 10 and leading to an appropriate control valve preferably such as will be described hereinafter.

A chamber 35 formed in the casting 13 above the gear pump and closed by the rear face of plate 10, communicates with a groove 36 which completely surrounds the gear pump chamber 28 and is closed by the rear face of plate 10. Chamber 35 also communicates with the opening 17 and chamber 21, surrounding the drive shaft 15, through passages 37 and 38, respectively. Liquid is supplied to the chamber 35 through a passage 39, from a source to be hereinafter described, so that the communicating groove 36, chamber 21 and openings 16 and 17 are always flooded and the gear pump chamber 28 is thus effectively sealed against the admission of air thereto. The level of the liquid in chamber 35 is determined by an overflow outlet 40, which communicates with a pipe 41 leading to the sump 30.

The shaft 15 also drives a variable displacement pump of a well known type. That shown in Figures 2 and 5 is similar in many respects to the pumps fully described in my issued Patent No. 1,619,200, and in my co-pending application Serial No. 87,791, filed February 12, 1926. It comprises a substantially circular driver 42 keyed to the inner end of the shaft 15 so as to rotate therewith about a fixed horizontal axis. Within the driver 42 is a cylinder barrel 43 mounted for rotation about a pintle 44, fixed in and projecting from a depending rock arm 45. The arm 45 is supported by an integral sleeve 46, rotatably mounted upon a hollow cylindrical stud 47, projecting horizontally from and firmly anchored in the upper portion of the casting 13. The cylinder barrel 43 is formed with a series of radial bores 48 each having a piston 49 reciprocable therein. Each piston is provided with a cross-head 50 which reacts through a roller bearing 51 against one of a series of tangential reaction faces 52 on the driver 42. Each bore 48 is formed with a port 53 arranged to communicate alternately with gashes 54 and 55, formed in the opposite sides of the pintle 44. A passage 56 communicating with gash 54 leads through the pintle to a passage 57 in the arm 45, and a similar passage 58 communicates with gash 55 and a second passage 59 in the arm 45. Passages 57 and 59 communicate with pipes 60 and 61, respectively, through separate tubes one of which is shown at 62 in Figure 5, in the manner described in the above entitled application. Tubes 62 form a flexible hydraulic connection between the rock arm 45 and a clamp element 63 firmly fixed upon the end of the stud 47 in a manner fully described in said application. The shaft 15 is driven at constant speed. When the arm 45 is in such position that the pintle 44 is concentric with the shaft 15 pump displacement

is zero and there is no flow in pipes 60 and 61, and when the arm is shifted toward the right (Fig. 5) so as to effect a laterally offset relation between the pintle and shaft the pump delivers liquid through passages 56 and 57 and pipe 60 at a rate determined by the degree of the offset relation and receives liquid through pipe 61 and passages 59 and 58 at a corresponding rate.

The clamp element 63 in this instance is extended to provide a rigid locating arm 64 disposed beside the rock arm 45. The locating arm carries a roller 65 which cooperates with a rotary cam 66 on the rock arm 45 to regulate the position thereof and thereby regulate pump displacement. The cam 66 is journaled in the rock arm 45 and is operated and controlled through appropriate gearing such as that described in my issued patent hereinabove mentioned. The gearing herein shown comprises a gear 67 connected to the cam 66 through a shaft 68, to which both are secured, an idler gear 69, carried by the rock arm, which meshes with gear 67 and with a gear 70, keyed to a rotary stem 71. The stem extends through the gear 70, hollow stud 47, casting 13 and plate 10, and at its exposed end carries an appropriate hand control lever 72 keyed thereto. An appropriate clamp nut 73 retains the gear 70 upon the end of the stem and cooperates with a collar 74 on the stem to retain the same against end play. The base of the hand lever 72 is preferably shaped to provide an indicating dial 76 having a suitable pointer 77 for co-operation with a graduated scale 78 formed on the front face of the plate 10. A second clamp nut 79 threaded on the forward end of the stem 71 serves to clamp the dial 76 against the face of the plate 10 to thereby releasably secure the same, and consequently the stem, in any position of rotative adjustment. The nut 79 is preferably equipped with an appropriate handle 80. Upon releasing the nut 79 the hand lever 72 may be swung in either direction through the range indicated by the scale 78, causing the stem 71 and gear 70 to rotate correspondingly. This rotation is transmitted through gears 69 and 67 to the cam 66 which reacts against the roller 65 to shift the rock arm 45 and consequently the pintle 44 toward or from concentric relation with the drive shaft 15. In this manner the displacement of the pump may be varied at will and thereafter retained in any position of adjustment by tightening the nut 79. Any suitable means such as a spring loaded tension bolt 81, connecting the fixed locating arm 64 with the rock arm 45, may be employed to normally retain the cam 66 against the roller 65.

Additional displacement regulating means is provided in the pump shown by which the displacement thereof may be temporarily increased over that which may have been de-

terminated by the setting of the adjustment just described. This additional regulating means may assume various forms and may be operated and controlled in various ways, but in this instance a fluid actuated piston 82 is provided for the purpose. The piston 82 is fitted for reciprocation within a cylinder 83, formed as an integral part of the fixed locating arm 64. A contact element 84, carried by the piston 82, is disposed to thrust against a pin 85, fixed in the rock arm 45, to thereby force the arm 45 toward the right (Fig. 5) when the piston 82 is advanced. A passage 86 in the arm 64 effects communication between the cylinder 83 and a pipe 87 through which fluid pressure is supplied under the control of mechanism to be herein-after described. The extent of advance of the piston 82 is regulated and controlled by appropriate means such as a tail rod 88, fixed to the piston and projecting outwardly through the end of the cylinder 83, and carrying a suitable nut 89 adjustably fixed thereon. The nut 89 serves as an adjustable stop which cooperates with the face 90 of the arm 64 to limit the advance of the piston 82. It will thus be understood that whenever fluid pressure is applied to pipe 87, the piston 82 is advanced to a position predetermined by the setting of the nut 89, the arm 45 is forced to the right to a corresponding predetermined position, and pump displacement is increased accordingly.

In the pump mechanism shown the discharge side of the constant displacement gear pump is permanently connected with the intake side of the variable displacement pump, and provision is made for maintaining the pressure within those connections substantially constant. In this instance the passage 34, hereinabove mentioned, which receives the discharge from the gear pump, communicates through a port 91, in the rear face of the plate 10, with the lower end of a vertical groove 92, formed in the front face of the casting 13 and closed by the coacting face of the plate 10. Groove 92 communicates at its upper end with a horizontal passage 93, which extends rearwardly through the casting 13, and communicates through a pipe 94 with the end chamber 95 of an appropriate low pressure relief valve. Pipe 61, leading to the intake side of the variable displacement pump also communicates with chamber 95. A second chamber 96 formed in the casting 13 communicates with the chamber 35, hereinbefore described, through the passage 39. A valve plunger 97, controlling communication between chambers 95 and 96, is yieldably retained in the position shown in Figure 6 by the pressure of a spring 98 housed within a bore 99 within the casting 13. Spring 98 is interposed between the plunger 97 and a tension adjusting screw 100 threaded in and projecting through the plate 10. In the position shown

the plunger 97 blocks communication between chambers 95 and 96. The plunger 97 assumes this position when the pump is at rest and when there is no pressure within the chamber 95. The capacity of the gear pump is somewhat greater than the demands upon it, however, so that when the pump mechanism is set in operation pressure builds up in the passages 33 and 34, port 91, groove 92, passage 93, pipe 94, chamber 95, and pipe 61, until the plunger 97 is forced back against the pressure in spring 98 and the excess liquid escapes into and through chamber 96 and passage 39 to the chamber 35. This condition maintains throughout the normal functioning of the pump mechanism so that a predetermined pressure, determined by the tension in spring 98, is maintained throughout the hydraulic connections just mentioned. The excess liquid discharged through the passage 39 into the chamber 35 serves to maintain a body of liquid within this chamber for the purposes hereinabove pointed out.

The hydraulic pressure maintained by the gear pump in the groove 92 may be utilized as a pressure supply source for operating some auxiliary mechanism with which the machine may be equipped. To this end a passage 101 is formed through the plate 10 in such position as to register with the groove 92, when the casting 13 is assembled therewith. An elbow 102 or other appropriate outlet element, attached to the front face of the plate 10, communicates with the passage 101 and provides an appropriate connection for receiving a pipe lead to such auxiliary mechanism. When no auxiliary mechanism is used the elbow is ordinarily plugged.

The discharge from the variable displacement pump is placed under the control of a distributing valve of appropriate type which, in the pump mechanism shown, is made a part of the plate 10. In this instance a horizontal bore 103 is formed within the lower portion of the plate extending from edge to edge thereof. This bore is closed by appropriate end caps 104 and 105 and at opposite ends is enlarged to form chambers 106 and 107. Passage 34, which receives the discharge from the gear pump, leads downwardly into end chamber 106. An annular groove 108, surrounding the bore 103, communicates through a passage 109 in the plate 10, with an elbow 110 fixed to the front of the plate and adapted to receive a pipe 111 constituting one side of a main motor circuit. A similar groove 112 communicates with a passage 113 which leads through the inner face of the plate 10. The pipe 60 which receives the discharge from the variable displacement pump is connected with this passage. A similar groove 114 communicates through a passage 115 in the plate 10, with an elbow 116, fixed to the front of the plate and adapted to receive a pipe 117 constituting the other side of a main motor cir-

cuit. A similar groove 118 communicates with a drain passage 119 which extends through the plate 10 and discharges rearwardly into the sump 30 beneath the pump mechanism. The forward end of drain passage 119 also communicates with an elbow 120, attached to the front of the plate 10, serving as a convenient pipe connection for carrying off the exhaust liquid from the auxiliary mechanism hereinabove referred to. When no auxiliary mechanism is employed this elbow 120 is plugged. A similar groove 121 communicates through a passage 122 in the plate to which the pipe 87 (leading to the pump displacement regulating cylinder 83) is connected.

The several grooves 108, 112, 114, 118, and 121 are controlled by a suitable valve plunger 123 mounted for lengthwise reciprocation within the bore 103. The plunger shown contains a longitudinal passage 124 through which communication is maintained between the end chambers 106 and 107. A piston head 125 on the plunger controls the groove 108, a similar head 126 controls the grooves 112 and 114, and a similar head 127 controls the groove 121. An elongated head 128, intermediate the heads 126 and 127, contains ports 129, which communicate with the longitudinal passage 124. Head 128 controls the groove 118 and cooperates with an annular chamber 130, surrounding the bore, to make and break communication between the groove 114 and ports 129. The plunger is designed to assume any one of the five positions shown in Figures 3, 7, 8, 9 and 10, and is actuated and controlled through a stem 131, connected to one end thereof, from any appropriate means such as a hand lever 132.

The motor driven by the pump is typified by a conventional cylinder 133, containing a piston 134, connected to a piston rod 135 projecting through one end only of the cylinder. Due to the liquid displaced by the rod, that end of the cylinder containing the rod is of less capacity than the other end, and will be hereinafter designated the "small end" to distinguish from the other hereinafter termed the "large end." It will be noted that pipe 111 communicates with the large end and pipe 117 with the small end of the cylinder.

In operation the drive shaft 15 is rotated at constant speed so that the gear pump, comprising the gears 26 and 27, draws liquid from the sump 30 through pipe 31 and passage 32 and forces the same through passages 33 and 34, port 91, groove 92, passage 93, pipe 94, and chamber 95 to the pipe 61 leading to the intake side of the variable displacement pump.

Due to the excess capacity of the gear pump over the demands upon it the valve plunger 97 is forced back against the pressure in spring 98, permitting the excess liquid to escape through chamber 96 and passage 39 to the chamber 35. A predetermined pressure

determined by the adjustment of screw 100 is thus maintained within the pipe 61 leading to the intake side of the variable displacement pump. This pressure is also transmitted through passage 34 to the end chamber 106 of the control valve, and also through the longitudinal passage 124 to the other end chamber 107. Both end chambers 106 and 107 and the interior of valve plunger 123 are thus maintained flooded with liquid under pressure. The shaft 15 also drives the driver 42 of the variable displacement pump at a constant rate so that this pump, receiving liquid through pipe 61, delivers the same through pipe 60 into the groove 112, at rate depending upon the position of the rock arm 45 and pintle 44.

With the plunger 123 of the control valve in the intermediate position shown in Figure 3, groove 112 is in open communication with end chamber 106, so that liquid discharged from the variable displacement pump passes through chamber 106, passage 34, port 91, groove 92, passage 93, pipe 94, and chamber 95 and returns to the variable displacement pump through pipe 61. This pump is thus by-passed, both sides thereof being exposed to the pressure maintained by the gear pump in chamber 95. With valve plunger 123 in this position groove 108 is also open to the pressure in end chamber 106 so that pipe 111, leading to the large end of the motor cylinder 133, is exposed to this pressure; but groove 114, communicating with the small end of the cylinder through pipe 117, opens into the dead space confined between the heads 126 and 130 so that there can be no flow through pipe 117 and the piston 134 is thus effectively blocked. It will also be noted that in this position of the valve plunger 123, groove 121 is open to the drain groove 118 so that pipe 87, leading to the stroke change cylinder 83, is open to exhaust and the rock arm 45 and pintle 44 assumes the position determined by the cam 66. As indicated in Figure 1 the control lever 72 for the cam 66 is in an intermediate position so that the variable displacement pump is operating at about one half of maximum capacity.

When by adjusting the hand lever 132 the valve plunger 123 is shifted into the position shown in Figure 9 groove 121 is still open to groove 118 and pump displacement remains unchanged. In this position of plunger 123 groove 112 communicates with groove 114 so that the liquid discharged from the variable displacement pump, through pipe 60, passes through these grooves and pipe 117 to the small end of the motor cylinder 133 so that the piston 134 is then driven toward the right at a rate dependent upon the setting of the cam 66. As the piston travels toward the right the liquid escapes from the large end of the cylinder through pipe 111, groove 108, end chamber 106, passage 34, etc. into the

chamber 95 from whence it escapes past the plunger 97 or through the pipe 61 back to the variable displacement pump. To increase the rate of travel of the piston 134 toward the right the valve plunger 123 is shifted into the position shown in Figure 10. In this position groove 112 is still open to groove 114 and groove 108 is still open to end chamber 106 so that the pump-motor circuit remains the same. But in this position groove 121 is exposed to the pressure in end chamber 107 so that the pressure is transmitted through pipe 87 to the cylinder 83, the piston 82 advances, and the element 84, engaging the pin 85 forces the rock arm 45 toward the right (Fig. 5) to increase the displacement of the variable displacement pump. This results in a corresponding increase in flow in pipes 60 and 117 with a corresponding increase in the rate of travel of the piston 134.

To operate the piston 134 at a relatively slow rate in the opposite direction the valve plunger 123 is shifted into the position shown in Figure 7, in which position groove 108 is closed to chamber 106 and open to groove 112, so that the liquid discharged by the pump through pipe 60 is directed through grooves 112 and 108 and pipe 111 to the large end of the cylinder 133. In this position of the plunger 123 groove 114 is closed to groove 112 and open to end chamber 106 through chamber 130, ports 129 and longitudinal passage 124 through the plunger, so that as the piston 134 is driven toward the left by the flow of liquid through pipes 60 and 111, liquid from the small end of the cylinder 133 passes through the end chamber 106 to the chamber 95 in the low pressure relief valve and thence through pipe 61 back to the variable displacement pump. Since the two ends of the cylinder 133 are of different capacities the large end consumes more liquid than is discharged from the small end. Due to this deficiency the liquid discharged from the small end of the cylinder to chamber 95 is supplemented by liquid supplied from the gear pump through passage 33 to thereby insure that the variable displacement pump may be supplied with liquid as fast as it is discharged therefrom. It will be noted that in the position of the valve plunger 123 shown in Figure 7 groove 121 is open to drain groove 118 so that the cylinder 83 is open to exhaust and the variable displacement pump is discharging at a relatively low rate determined by the setting of the cam 66.

To increase the rate of travel of the piston 134 toward the left the plunger 123 is shifted into the position shown in Figure 8, in which position groove 121 is exposed to the pressure in end chamber 107 and the piston 82 (Fig. 5) is again advanced to increase pump displacement and thereby increase the rate of flow through pipe 60 to the groove 112.

Also groove 114 is closed to chamber 130 and open to groove 108 so that as the piston 134 continues its travel toward the left the liquid discharged from the small end thereof, through pipe 117, is directed through grooves 114 and 108 to the pipe 111 to thereby supplement the liquid supplied from the pump through groove 112 to effect a corresponding further increase in the rate of travel of the piston. When both ends of the cylinder 133 are thus exposed to the delivery side of the pump the piston 134 travels toward the left by reason of the fact that the effective area of the left end face of the piston is reduced by the piston rod connection.

Provision is made in the pump mechanism shown for protecting the circuit against excessive pressures and to this end a high pressure relief valve is provided connected to the delivery pipe 60 leading from the variable displacement pump. A relief valve for this purpose is shown in Figure 6. In this instance this valve comprises an element 140 normally seated over and closing the end of a bore 141 formed in the casting 13. A star shaped stem 142 connected with the element 140 and guided within the bore 141 insures proper seating of the element. The bore 141 communicates through a pipe 60' with the delivery pipe 60. The element 140 is yieldably held in closed position by a heavy spring 143, housed within an enlarged bore 144 in the casting 13 and interposed between the element and a suitable adjusting screw 145 threaded in and projecting through the plate 10. The bore 144 is provided with an appropriate outlet port 146 through which liquid escaping past the valve element 140 may pass and return to the sump 30 below.

Various changes may be made in the embodiment of the invention hereinabove specifically described without departing from or sacrificing any of the advantages of the invention as defined in the appended claims.

I claim:

1. In a device of the character described the combination of a plate, a variable displacement pump supported thereby, driving means for said pump supported by and extended through said plate, and pump regulating means supported by said plate.

2. In a device of the character described the combination of a plate, a pump supported thereby, shafting supported by and extended through said plate for driving said pump, and valve mechanism supported by said plate for controlling the liquid discharged by said pump.

3. In a device of the character described the combination of a plate, a drive shaft extended through said plate, a variable displacement pump supported by said plate and driven by said shaft, a second pump supported by said plate and driven by said shaft,

and means supported by said plate for controlling the discharge from said pumps.

4. In a device of the character described the combination of a plate, a drive shaft extended through said plate, a variable displacement pump supported by said plate and driven by said shaft, pump regulating means supported by said plate, passages in said plate for connection with a hydraulic circuit, and hydraulic connections between said pump and passages.

5. In a device of the character described the combination of a frame having an opening, a plate attachable to said frame over said opening, a variable displacement pump carried by said plate, pump driving means extended through and carried by said plate, and pump regulating means carried by said plate, said pump and both of said means being combined for projection as a unit through said opening upon application of said plate to said frame.

6. In a device of the character described the combination of a plate, a casting fixed to and supported by said plate, a pump supported by said casting, said plate having means for connection with a hydraulic circuit, hydraulic connections between said pump and means, and a valve supported by said plate for controlling said connections.

7. In a device of the character described the combination of a variable displacement pump, fluid actuated means for varying pump displacement, valve mechanism for receiving and directing the flow of liquid discharged by said pump, and fluid connections controlled by said valve mechanism for controlling said displacement varying means.

8. In a device of the character described the combination of a variable displacement pump, fluid actuated means for varying pump displacement, valve mechanism for receiving and directing the flow of liquid discharged by said pump, and means responsive to adjustment of said valve mechanism for controlling the operation of said displacement varying means.

9. In a device of the character described the combination of a variable displacement pump, hydraulically actuated means for varying pump displacement, valve mechanism for receiving and directing the flow of liquid discharged by said pump, a second pump, and means responsive to adjustment of said valve mechanism for controlling communication between said second pump and said displacement varying means.

10. In a device of the character described the combination of a variable displacement pump, a second pump, hydraulic connections between said pumps, a liquid reservoir below said second pump, a hydraulic connection between said reservoir and second pump, and means providing a liquid seal for said second pump to prevent the admission of air thereto.

11. In a device of the character described

the combination of a pump housing, having inlet and outlet passages, cooperating liquid impelling elements within said housing and coacting therewith to induce a liquid flow between said passages, a liquid reservoir below said housing, a hydraulic connection between said reservoir and said inlet passage, and means providing a liquid seal for said housing to prevent the admission of air thereto.

12. In a device of the character described the combination of a pump housing having inlet and outlet passages, liquid impelling means within said housing for inducing a liquid flow between said passages, a liquid reservoir, a hydraulic connection between said reservoir and inlet passage, a pressure relief valve, and means providing a liquid seal for said housing to prevent the admission of air thereto, said means including an auxiliary chamber supplied with liquid discharged from said relief valve.

13. In a device of the character described the combination of a pump housing having a shaft receiving opening and inlet and outlet passages, a drive shaft in said opening, liquid impelling means within said housing for inducing a liquid flow between said passages, a liquid reservoir, a hydraulic connection between said reservoir and inlet passage, and means providing a liquid seal for said housing to prevent the admission of air thereto, said means including an auxiliary liquid retaining chamber open to said opening to flood the same.

14. In a device of the character described the combination of a variable displacement pump, a hydraulic circuit fed thereby, means adjustable by the operator for initially determining pump displacement, valve mechanism for controlling communication between said pump and circuit, and means controlled by said valve mechanism for modifying pump displacement.

15. In a device of the character described the combination of a variable displacement pump, means adjustable by the operator for initially determining pump displacement, additional means for modifying pump displacement, and valve means for controlling the operation of said last named means.

16. In a device of the character described the combination of a plate, a variable displacement pump supported thereby, means supported by and operable through said plate for initially determining pump displacement, fluid actuated means supported by said plate for modifying pump displacement, and means supported by said plate for controlling said last named means.

17. In a device of the character described the combination of a support, a variable displacement pump supported thereby, a rock arm adjustable on said support to vary pump displacement, means adjustable by the oper-

ator for initially determining the position of said arm, fluid actuated means for shifting said arm from the position initially set, and adjustable means for accurately limiting the 5 action of said last named means.

18. In a device of the character described the combination of a plate, a casting supported thereby, a variable displacement pump supported by said casting, a second pump, 10 cooperating fluid passages in said plate and casting for connecting said pumps, shafting extended through said plate for driving said pumps, means on said plate for connection with a hydraulic circuit, hydraulic connections 15 between said last named means and said variable displacement pump, addition means on said plate for connection with an auxiliary hydraulic circuit, hydraulic connections between said last named means and said 20 second pump, and means operable through said plate for varying the displacement of said first named pump.

19. The combination of a variable displacement pump, displacement regulating means, 25 a hydraulic circuit, valve mechanism between said pump and circuit adjustable to vary the direction of flow therein, a second pump, and hydraulic connections between said second pump and circuit controlled by said valve 30 mechanism.

In witness whereof, I hereunto subscribe
my name this 15th day of June, 1927.

JOHN P. FERRIS.
